(57) **CLAIM**

The ornamental design for a watch case, as shown and described.

DESCRIPTION

FIG. 1 is a front elevation of a watch case showing my new design;

FIG. 2 is a rear elevation thereof;

FIG. 3 is a right side elevation thereof; and,

FIG. 4 is a rear perspective view of the watch case on an enlarged scale.

The broken lines are for illustrative purposes only and form no part of the claimed design.
